C. G. HAWLEY
Inventor.

UNITED STATES PATENT OFFICE

CHARLES GILBERT HAWLEY, OF CHICAGO, ILLINOIS, ASSIGNOR TO LOCOMOTIVE FIRE-
BOX COMPANY, OF CHICAGO, ILLINOIS, A CORPORATION OF DELAWARE

LOCOMOTIVE BOILER

Application filed May 13, 1922. Serial No. 560,661.

My invention relates to locomotive boilers and the object thereof is to increase the capacity and efficiency of such boilers. To that end I very considerably increase the firebox heating surface and provide means which cause or set up a positive fore-and-aft circulation of the water in the boiler.

My invention comprises a locomotive firebox in combination with a hollow vertical water wall of inverted triangular form which hangs from the crown sheet of the firebox and extends longitudinally in the firebox from a position near the flue sheet thereof to a point near the back end or head of the firebox. To this wall I connect a plurality of water feeding tubes. These preferably extend from the side water legs of the firebox to and into the bottom of the water wall. Said bottom of the wall is inclined upwardly and rearwardly and the connecting tubes, as a group or groups, while in themselves substantially horizontal, conform to the inclination of the bottom of the water wall. Thereby the wall is supplied from numerous points in the side water legs from different elevations therein. An important incident of my invention is that these supply tubes are extended nearly to the outside shell or wrapper sheet of the firebox, taking water therefrom rather than from the side-sheets of the firebox, thus avoiding any confusion or congestion of water currents which might occasion difficulty with the side sheets stay-bolts. A further important incident of the invention is the combination, with the described supply tubes, of a sectional fire-brick arch for which said tubes provide ideal supports.

The foregoing and other features of my invention will be readily understood on reference to the accompanying drawings, in which Fig. 1 is a vertical cross section of a locomotive firebox of the narrow type; embodying my invention; Fig. 2 is a like view of a wide firebox, embodying my invention; Fig. 3 is a vertical longitudinal section substantially on either of the lines 3-3 of Figs. 1 and 2; Fig. 4 illustrates a modification of the invention wherein two vertical water walls are employed with a peculiar arrangement of the water supply tubes; Fig. 5 is a longitudinal

section thereof on either of the lines 5-5 or 5'-5' of Fig. 4; Fig. 6 is a further modification of the invention; Fig. 7 is a vertical section thereof on the line 7-7 of Fig. 6; Fig. 8 is a partial transverse section on the line 8-8 of Fig. 7; Fig. 9 is a transverse section showing still another form of the invention; Fig. 10 is a section thereof on the line 10-10 of Fig. 9; Fig. 11 is a horizontal section enlarged taken on any of the lines 11 of the several figures; Figs. 12 and 13 are sectional details, showing different ways of securing the supply tubes in the water walls.

I have herein shown fireboxes of different shapes or types in order that it may be clearly understood that my invention is applicable to all thereof. All forms of the invention are much the same, notwithstanding slight modifications of shape or assembly as between water wall and the water feeding and arch supporting tubes. The simplest forms are illustrated in Figs. 1, 2 and 3, wherein A represents the hereinbefore mentioned hollow water wall. As shown in Fig. 3 this wall is stay-bolted throughout and is of substantially triangular form. Its front end or edge A' is set back far enough from the flue sheet 2 of the firebox to permit necessary work to be done on the flues of the boiler. The rear end of the wall A reaches almost to the back sheet 3 of the firebox; thus a wall of large area is secured. Sufficient firing clearance 4 is allowed between the grate (not shown) and the lower end or inverted apex A'' of the wall. As shown in Figs. 1 and 2, the wall is positioned midway between the side sheets 5, 5, of the firebox. As suggested by the several figures, the tubes B (above mentioned) may be of various lengths and shapes. A plurality of such tubes is provided on each side of the wall and each tube serves to connect a side water leg 6 of the boiler with the interior or the water wall A. As well shown in Fig. 3 the tubes enter the wall close to the inclined bottom thereof. Hence, the series or groups of tubes, as a whole, has the same, or substantially the same, inclination.

Upon the tubes I place the firebrick C, which, as well known, constitute a sectional fire arch or baffle of a form which is most con-

venient and desirable. The several bricks may be separately laid upon the supporting tubes B and likewise may be separately removed therefrom. It is entirely unnecessary 5 to destroy any considerable part of the arch for the mere sake of getting at the different parts of the firebox.

As clearly shown, the outer ends of the tubes extend considerably beyond the side sheets of the firebox and almost to the wrapper sheet or boiler shell 7. Thus, the tubes and the water wall are caused to draw water from points adjacent the shell rather than from points adjacent the fire sheets of the fire box. As well 10 known, when the boiler is under fire there is a rapid rise of water adjacent each side sheet and concurrently a well defined downward flow of cooler water adjacent outer or wrapper sheets 7. It is this cooler supply which 15 is taken into the water wall through the connecting tubes B. By this simple expedient I avoid all possibility of interference or congested water or steam pockets upon the side sheets; and thus avoid all difficulty with the 20 side sheets and the many stay-bolts therein.

In Figs. 4 and 5 I have illustrated two of the water walls D, D, with a peculiar set of connecting tubes which serve to support the arch brick C' and by which each water wall is 25 supplied with water from both water legs of the boiler. In this arrangement the lower tubes E are individual to respective walls D. From that point upward the tubes are alternately individual, first to one and then to the 30 other of the walls, thus the tube D¹ extends from the side water leg 12 to the left-hand water wall D; the tube D² extends from the left-hand water leg 12' to the left-hand water wall D. This condition is reversed as to the next 35 set of tubes D⁴ and D³, which are joined to the right-hand water wall D. An incident of 40 this construction and one of very considerable importance is depicted in Fig. 5, to wit, the arch as a whole is deeply corrugated by many 45 and variously positioned pockets 13. Such an arch serves to thoroughly admix the gaseous combustibles which flow upward and rearward from the fuel bed, following the direction of the arrows 14 in Fig. 5. This positive admixing effect of the arch is also to be 50 observed from Figs. 1, 2 and 3, wherein the arches may be regarded as being composed of the tubes and firebrick, also as shown.

Fig. 6 is like unto Fig. 4, but comprehends 55 only individual row or series of tubes F for each water wall G. These tubes support firebrick 15 as shown in Fig. 7, the same constituting the desired arches in the side passages. The middle passage, namely the space be- 60 tween the two walls G, is occupied by a middle row of firebrick H, which may be supported from studs 16 projecting from the walls G.

The structure of Figs. 9 and 10 differs from 65 the others in that only one large water tube I is employed for the one or more water walls

J. This tube, as shown in Fig. 9, may extend from side to side of the firebox, in which case it should be applied thereto through the medium of the diaphragm plates 17. Or the tube I may be divided and a part appropriate 70 to each water wall as indicated by the tube 18 of Fig. 8. In such cases the structure should be reinforced by a tie-rod or stay-bolt 19, extending from the inner side of the water wall to the shell of the boiler. The 75 structure of Fig. 8 is also appropriate to one or all of the tubes of Figs. 6 and 7.

The detailed Figs. 11, 12 and 13 illustrating the structure of the water wall, are self-explanatory. In each of these figures the water 80 wall is marked 20, the supply tubes are marked 21 and the stay-bolts of the wall are marked 22.

Various modifications of my invention will 85 readily suggest themselves to one who is skilled in the art, and therefore I do not limit the invention to the precise shapes, constructions and combination of parts herein shown.

Having thus described my invention, I 90 claim as new and desire to secure by Letters Patent:

In combination with a locomotive boiler having a firebox including a crown sheet and side sheets, a flat tubular water wall arranged longitudinally of the firebox and depending 95 from and opening through the crown sheet thereof, said water wall having an upwardly and rearwardly inclined bottom wall, and a plurality of transversely extending supply tubes connecting said water wall with the 100 side sheets of the firebox, said tubes being arranged in spaced relation in the plane of the inclined bottom wall of the water wall and extending at their outer ends beyond the side sheets of the firebox.

In testimony whereof, I have hereunto set my hand this 6th day of May, 1922.

CHARLES GILBERT HAWLEY.
